CLAIM

The ornamental design for a display screen having a graphical user interface or portion thereof, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a top plan view of a display screen having a graphical user interface or portion thereof.

The broken lines representing features of the display screen having a graphical user interface or portion thereof including the display screen itself form no part of the claimed design.

2047 REMARKS 26 10 MIN CYCLING

HEART RATE: 124 BPM
ZONE: 3

A dense, abstract drawing of a tree with a thick trunk and many branches, rendered in white ink on a dark background. The tree is highly detailed, with many small leaves and intricate branch patterns. The style is reminiscent of traditional East Asian ink wash painting.
